UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF MICHIGAN.

TOY MACHINE GUN.

Application filed November 29, 1926. Serial No. 151,309.

My invention relates to a toy machine-gun and an object of my improvement is to produce an apparatus that shall simulate a machine-gun in appearance and action and that may be cheaply and conveniently made and assembled.

I attain this object in the device illustrated in the accompanying drawings, in which:—

Figure 1 is a side elevation of an apparatus embodying my invention, part of the casing being broken away.

Figure 2 is a section on the line II—II Figure 1.

Figure 3 is a longitudinal vertical section, a part of the apparatus being broken away to economize space.

Figure 4 is a section, similar to Figure 3, the parts being shown in a different position.

a is a base plate supported upon legs a² 20 a² to form a standard or support for the gun parts. b is a sheet metal standard in the form of a casing rising from the base a and having the barrel g secured at its upper end.

The barrel g has an enlargement g² at its 25 outer end. g³ is a longitudinal slot through the lower wall of the enlargement g² and g³ is a slot through the lower wall of the barrel g toward the rear end of said barrel within the casing b. g⁴ is a lug turned inward 30 from the material of which the barrel is composed.

j is the retracting wire in the barrel g bent vertically downward to form the lug j² extending at its rear end vertically downward through the slot g³. j³ is a piston fitting and adapted to reciprocate in the barrel g and secured to the forward end of the retracting wire j. k is a spring interposed between the lug g⁴ and the piston j³. The retracting wire j is bent downward and upward to form a loop j⁴ extending through the slot g³. h is a cork adapted to fit tight in the forward end of the barrel g and to be guided in its motion by the wall of the enlargement g² of the barrel g. m is a wire having its rear end bent and engaged in the loop j⁴ and having its forward end bent upward extending through the slot g³ and formed into a loop m³ that shall engage the 50 outer end of the cork h.

c is a shaft parallel to the barrel g and resting in bearings in the end walls of the standard b. c² is a crank formed at the outer end of the shaft c. d is a sleeve upon the shaft c having its ends bearing against the

forward and rear inner walls of the standard b. e is a disc secured upon the sleeve d in a plane at right angles to said sleeve and having arcuate cams extending rearwardly from its periphery, said cams having slanting edges e² and vertical edges e³. Said cams are adapted to engage the lug j² with their edges e² to retract the wire j and then to release said lug as the vertical faces e³ pass by the same. cd is a pin fastening the sleeve 60 b and shaft c together. Said pin is turned over at its upper end at ed to engage an aperture in the disc e to secure said disc to said sleeve and shaft.

f is a casing enclosing the operating parts 70 of the gun.

The operation of the above described device is as follows:

The operator turns the shaft c by means of the crank c². This carries with it the 75 sleeve d and disc e. A slanting face e² of a cam engages the lug j² and draws the wire j back against the action of the spring k. This carries with it the wire m which forces the cork h back and into the barrel g as 80 shown in Figure 3. When the face e³ of the cam is beyond the lug j² the wire j is released and the spring k forces the piston j³ forward compressing the air between it and the cork h and forcing the cork out of the barrel, 85 as shown in Figure 4, thus releasing the compressed air and causing the report of the gun.

The shaft c and attached parts may be turned as rapidly as desired creating a series 90 of correspondingly rapid reports.

What I claim is:

1. In an apparatus of the kind described, the combination of a barrel, a piston adapted to reciprocate in said barrel, a spring acting 95 to press said piston forward, a wire rigidly secured to said piston and extending rearwardly therefrom, a cork adapted to be inserted in said barrel in front of said piston, means for guiding said cork into position in 100 said barrel, a wire secured to said first mentioned wire to move therewith and adapted to engage said piston to force the same into position in said barrel when said piston is retracted and means for continuously re- 105 tracting and releasing said first mentioned wire.

2. In an apparatus of the kind described, the combination of a barrel having a piston adapted to reciprocate air tight therein, a 110

projecting spring for said piston, a stopper closing the end of the barrel air tight in front of said piston, said stopper being adapted to be displaced by the air compressed between it and said piston when the latter is projected by said springs, means for replacing said stopper when retracted, and a continuously acting means for retracting said piston and replacing means and releasing the same.

3. In an apparatus of the kind described, the combination of a barrel, a piston adapted to reciprocate in said barrel, a spring acting to press said piston forward, a wire rigidly secured to said piston and extending rearwardly therefrom, a cork adapted to be inserted in said barrel in front of said piston, means for guiding said cork into position in said barrel, a wire secured to said first mentioned wire to move therewith and adapted to engage said cork to force the same into position in said barrel when said piston is retracted and means for continuously retracting and releasing said first mentioned wire, said retracting and releasing means consisting in a rotatable cam engaging the first mentioned wire.

4. In an apparatus of the kind described, the combination of a barrel, a piston adapted to reciprocate therein, a spring acting to press said piston forward, a wire rigidly se-

cured to said piston and extending rearwardly therefrom, a cork adapted to be inserted in said barrel in front of said piston, means for guiding said cork into position in said barrel, said wire being bent downward at its rear end, a second wire adapted to engage and be disengaged from the forward end of said cork extending downward and backward and engaging said first mentioned wire toward the rear end thereof, and a continuously rotatable cam engaging the down-turned portion of the first mentioned wire to retract and release said wire.

5. In an apparatus of the kind described, the combination of a barrel, a piston in said barrel, an actuating spring for said piston, a cork adapted to close the outer end of said barrel and to be displaced therefrom to produce a report when the piston is driven forward, means for replacing said cork, a shaft having a crank located at the rear of and beneath said barrel and extending parallel thereto, a cam on said shaft adapted to act parallel thereto, and a lug connected with said piston and replacing means, said cam being adapted to retract and release said lug to retract the piston, replace said cork and to release said piston and cork.

In testimony whereof, I sign this specification.

WILLIAM F. SCHMIDT.
